DESIGN FOR A SURFACING MACHINE

Robert E. Wolfe and Richard F. Kneisley, Toledo,
Ohio, assignors to The American Floor Sur-
facing Machine Company, Toledo, Ohio, a cor-
poration of Ohio

Application December 5, 1938, Serial No. 81,588

Term of patent 14 years

To all whom it may concern:

Be it known that we, Robert E. Wolfe and Richard F. Kneisley, residents of Toledo, Lucas County, Ohio, have invented a new, original, and ornamental Design for a Surfacing Machine, of which the following is a specification, reference being had to the accompanying drawing, forming a part thereof.

In the drawing:

Figure 1 is a side elevation of the surfacing ma-
chine showing our new design;

Figure 2 is a top plan view thereof; and
Figure 3 is a rear end elevation thereof.
The dominant features of my design reside in
the portions shown in full lines.

We claim:

The ornamental design for a surfacing ma-
chine, as shown and described.

ROBERT E. WOLFE.
RICHARD F. KNEISLEY.
